UNITED STATES PATENT OFFICE.

FRANCIS NESBITT POIGNAND, OF WESTFIELD, NEW JERSEY, ASSIGNOR, BY MESNE ASSIGNMENTS, TO SUPER GAS CORPORATION.

METHOD OF AND APPARATUS FOR PRODUCING AND BURNING GAS IN STEAM LOCOMOTIVES.

Application filed April 9, 1926. Serial No. 100,886.

The main object of this invention is to provide an apparatus for the production of required units of heat in connection with the boiler system of a locomotive by the use of 5 steam and hydrocarbon, the apparatus converting the materials into gases and burning the resultant gases within the locomotive fire box.

Another object of the invention is to provide an apparatus wherein saturated or low 10 pressure steam will be first highly superheated and will then receive a spray of petroleum or other hydrocarbon, or carbonaceous materials, and the whole reacted into a 15 gas at a comparatively low pressure and a very high degree of heat.

Another object of the invention is to provide a retort or reaction chamber formed 20 of nickel, as pure as it is commercially possible to use it, and to deliver the steam and oil within the retort, and to react them therein in such manner as to produce, substantially, a blanket or layer of hydrogen around the inner wall of the retort. The 25 purpose of constructing the retort of pure nickel or nickel as pure as it is commercially possible to obtain and use it, is to provide a retort of metal having a large hydrogen absorbing capacity. The purer the nickel 30 the greater its hydrogen absorbing capacity. The temperatures developed in the fire-box are considerably above the melting point of nickel and if it were not for the presence of hydrogen within the retort, and the absorption 35 of the hydrogen by the nickel, the retort would be destroyed.

Another object of the invention is to construct the entire gas-forming apparatus of nickel so that any part of the apparatus subject to a destructive temperature will be 40 protected by hydrogen. A temperature sufficiently high to destroy the nickel will be sufficiently high to disassociate the elements of the steam introduced into the apparatus and 45 thereby produce hydrogen in sufficient quantities to protect the nickel from the exterior heat.

Another object of the invention is to provide a retort method of producing and 50 burning gas containing hydrogen, by means of which very high temperatures (above 1800° F.) may be produced around the retort without melting the metal of the retort.

It will, of course, be understood that

while the invention is illustrated and described as applied to and arranged within a locomotive fire box, it may be equally well applied and arranged within any form of furnace where it is desired to produce a very 55 high degree of heat.

In the drawings:

Fig. 1 is a longitudinal vertical sectional view of the apparatus within the fire box of a locomotive;

Fig. 2 a horizontal sectional view taken 65 on the lines 2—2 of Fig. 1;

Fig. 3 a detail vertical transverse sectional view of the retort;

Fig. 4 a bottom plan view of the retort;

Fig. 5 a detail plan view of the base on 70 which the retort is supported;

Fig. 5^a a detail perspective view of one of the segmental sections of the retort support;

Fig. 6 a vertical transverse sectional view 75 taken on the line 6—6 of Fig. 1;

Fig. 7 a detail plan view partly in section of the lower header of the superheater;

Fig. 8 a detail sectional view of one of the screw-threaded joints between the super- 80 heater tubes and the headers; and

Fig. 9 a transverse sectional view of one of the superheater tubes taken on the line 9—9 of Fig. 8.

Referring to the various parts by numerals, 1 designates the fire box of a steam locomotive; 2 the fire box base or pan, and 3 the usual fire tubes which lead from the fire box. On the pan 2 and around the walls of the fire box is arranged an interior lining or 90 wall 3^a of fire brick or other refractory material. This is for the purpose of protecting the metal walls of the fire box.

The apparatus comprises a retort and burner A and a superheater B, both of which 95 are mounted in the fire box, the superheater being arranged between the retort and the fire tubes of the boiler. The superheater is formed with a lower header 4 and an upper header 5, these headers being connected together by suitable, vertically extending, parallel tubes, as hereinafter described. The lower header is formed at its forward side, that is to say the side toward the fire flues of the boiler, with an entrance chamber 6, 105 at the center of which is arranged a depending flanged inlet 7. To this flanged inlet is connected a low-pressure steam supply pipe.

The header 4 at its rear side, that is to say the side toward the retort, is formed with an exit or outlet chamber 8, and to this chamber is connected an outlet pipe or conduit 9. This conduit or pipe is connected to the chamber 8 through the lower wall thereof, as shown clearly in Fig. 1. The chambers 6 and 8 are separated from each other by spaced walls 10 and 11 between which is formed an air space for cooling purposes and to prevent the hot gases or vapors in chamber 8 directly engaging and heating the wall of the entrance chamber 6. The upper wall of the inlet chamber is formed with two upwardly extending threaded nipples or tube connections 12, and the upper wall of the outlet chamber is formed with three upwardly extending threaded nipples 13, all of these threaded connections being symmetrically placed and uniformly spaced apart. Vertically extending superheater tubes 14 are connected to the threaded nipples 12 and 13, and the upper ends of these tubes are connected to depending threaded nipples 15 formed on the lower wall of the upper header. Steam entering the chamber 6 through the inlet 7 will therefore pass to the upper header through two of the tubes 14, and from the upper header will pass down to the outlet chamber through three of the tubes. This is to provide for the expansion of the steam within the superheater and to prevent undue acceleration of the steam and undue pressure. The superheater tubes have a short cylindrical portion at each end, for the threaded connections, and between said cylindrical ends the tubes are fluted or ribbed to provide the maximum heating surfaces. The ends of the tubes are each connected to a threaded nipple of a header by means of a threaded ring 16 which is screwed on the end of the tube and abuts against the outer end of the nipple on the header. Screwed on the threaded nipple is a union, or ring-like clamping nut 17, said nut being provided with an inwardly extending flange or portion which overlies the ring 16 and clamps it firmly against the end of the nipple. The tubes are therefore supported by their engagement with the rings 16, and the threaded engagement between the rings and the threaded ends of the tubes is relied upon to form steam-tight joints. These threads are comparatively fine and the rings 16 are comparatively thick in order to give satisfactory steam-tight joints and supports for the superheater tubes.

The superheater is supported in a depending hanger 18 secured to the under side of the fire box pan 2. The lower header 4 extends through an opening in the said pan, with the upper wall of the header substantially on a level with said pan or slightly above it. The superheater extends upwardly

through an opening formed in the fire brick floor 3^a of the fire box, as shown in Fig. 1. At the rear of the superheater is supported a vertical plate 19 of carborundum or other suitable refractory material, said plate being provided with a central aperture. This plate partially shields the lower portion of the superheater from the heat of the burning gases within the fire box.

The retort or re-action chamber 20 is mounted on a carborundum base 21, said base being placed directly on the pan or base plate 2 of the fire box. The retort consists of a hollow shell which is substantially circular in outline in longitudinal vertical section, as shown in Fig. 1, with the lower wall flattened to form a substantial support. In transverse sectional view, as shown in Fig. 6, the retort is rounded at its top and bottom but flattened at its sides, the side walls being substantially straight and vertical and merging into the top and bottom walls on a curve. The side walls also merge at their ends into the curved central part of the retort. As shown in plan view the retort is slightly longer fore-and-aft of the fire box than transversely thereof. The upper wall of the retort, at the center thereof, is depressed or extended inwardly into the retort to form a depending central point or apex 22. The inner wall of this central depending portion is curved and merged smoothly into the curved inner wall of the retort, said point forming approximately an inverted cone within the retort at the upper central portion thereof. The flattened bottom portion of the retort is formed with an annular series of depending flanged bosses 23. The inner and outer edges of these flanged bosses are concentric. The side edges thereof are tangential and the adjacent sides of the bosses are spaced apart a suitable distance and are parallel with each other to form radiating gas channels 24. Within the retort is formed a central upwardly extending outlet tube 25, the lower end of the tube merging into the bottom wall of the retort substantially co-incident with the inner ends of the flanged bosses 23, as shown clearly in Fig. 1. The tube 25 extends into the retort slightly above the center thereof and is open at its upper end. The lower end of this tube forms a large central discharge which is in direct communication with the gas channels 24. The tube 25 is formed with inwardly extending vertical ribs 26, and within said tube is arranged a central vertical inlet pipe 27. The ribs 26 serve to center this pipe and hold it in vertical position. The pipe 27 is formed near its lower end with a flange 28 by means of which it is secured to the under side of the pan 2. This pipe is also formed with a horizontal extension 29 which is connected to the end of the outlet pipe or con-

duit 9 leading from the lower header 4. The inlet pipe 27 extends upwardly to a point just slightly below the apex 22, the pipe being arranged concentric to said apex; 5 that is, the apex is directly in line with the vertical axis of the pipe. In the upper end of the inlet pipe is arranged a central vertically extending discharge nozzle 30, said nozzle being directly below the apex 22 and 10 arranged to discharge superheated steam on it. The lower end of the nozzle is connected to a tubular boss 31 which leads out through and to the outer side of the pipe 27. To the outer end of this tubular boss is connected 15 a pilot supply pipe 32 which leads down through the outlet tube 25 and between the wall of said tube and the exterior of the inlet tube 27 and into the horizontal portion 29 of the inlet pipe, said pipe 32 entering 20 the pipe 29 at 33. Axially in line with the pipe 27 the portion 29 thereof is provided with an aperture into which extends an oil 25 ejector nozzle shown in Fig. 1. The interior of the retort or re-action chamber 20 is formed with suitable vertically arranged 30 strengthening ribs, said ribs being preferably formed on the flat side walls of the retort. The pipe or conduit connecting the superheater to the inlet or intake pipe of the retort is enclosed within a suitable box or casing 38.

The base 21 which supports the retort is 35 preferably formed of carborundum, but it may be formed of any suitable refractory material. This base may be constructed in any suitable manner. As shown in the drawings it consists of a substantially flat circular base of suitable thickness placed directly on the upper side of the pan 2. This base 40 is formed of segmental sections which fit together around the inlet pipe 27 as a center. The base is preferably equal in diameter to the distance between the inner surfaces of the side walls of the fire box, as shown 45 clearly in Fig. 2. On these segmental sections are formed upwardly extending bosses 34 which co-incide in outline with the depending flanged bosses formed on the bottom of the retort. The bosses 23 of the retort fit squarely on the upwardly extending bosses 34 of the base. Between the bosses on the base are formed radially extending gas channels 35, the inner ends of these channels communicating directly with the open 50 lower end of the discharge tube 25 of the retort. As shown in Fig. 5, the divisional lines between the segmental sections of the base pass through the centers of the bosses 34. Of course it will be understood that the base 55 may be formed in any suitable manner, that shown in the drawings being a convenient way to make the base and serving as an illustration of one manner in which it may be constructed. The retort is bolted to the base 60 by bolts 36 which pass upwardly through the pan 2, through apertures in the carborundum base and into threaded apertures in the flanged bosses 23. It will be understood that the retort may be secured to the base in any suitable manner. Around the 65 circumference of the base is arranged a low wall of deflector bricks 37. These bricks rest on the pan 2 with their inner walls engaging the periphery of the base and their outer walls engaging the fire brick floor of the fire box. The upper ends of these deflector bricks extend a suitable distance above the fire brick floor and serve to deflect the burning gases upwardly around the retort. Through the base, outwardly from 70 each of the radial gas channels, are formed air openings 39, said openings extending down through the pan of the fire box so that air will be supplied in sufficient quantities to support combustion.

The retort and the superheater and all of the metal parts thereof are formed of pure nickel, that is to say of nickel as pure as it is commercially possible to obtain and work it. The gas produced and burned in this apparatus has a high percentage of hydrogen and produces extremely high temperatures—temperatures considerably above the melting point of nickel. However, nickel of the proper degree of purity will absorb 75 hydrogen and protect itself from the high temperatures outside of the retort, as will be more fully hereinafter described. It is a well established fact that the maximum of transfer of heat through pure nickel is 80 reached at approximately 1600° F. Above that temperature the rate of transfer of heat through the nickel is not increased.

The operation of the apparatus is as follows:

A fire is started in the combustion chamber in any suitable manner. Preferably ordinary cotton waste is saturated with oil and ignited. This primarily heats the retort and the superheater and serves to ignite the steam and oil vapors which first pass through the retort. When a temperature has been reached high enough to re-act the fuel materials into gas within the retort, the gas escapes from the retort and is burned. The very high temperature necessary for the complete re-action of the fuel materials is gradually reached through the increasing temperature due to the burning vapors and finally the burning of the pure gas.

Steam is admitted through the inlet 7 into the inlet chamber 6 of the lower header. From chamber 6 the steam passes upwardly through the two tubes 14 connected thereto and enters the upper header 5. From the upper header 5 the steam passes downwardly through three tubes connected thereto and enters the outlet chamber 8 of the lower header. From said chamber the superheated steam passes through the pipes 9 and 29 at 125 130

low pressure, into the intake pipe 27 of the retort. Part of the superheated steam enters the pilot pipe at 33 and is discharged through the nozzle 30 directly on the apex 22. Petroleum, or other hydrocarbon, or other carbonaceous material, is sprayed into the intake pipe through the ejector and passes upwardly with the superheated steam and is discharged at the upper end of the pipe 27 into the retort or re-action chamber 20. From the retort 20 the gas passes into the upper end of the discharge tube 25 and then downwardly through said tube and out through the radial gas channels 24 and 35 into the space surrounded by the wall of the deflector bricks 37. At this point the gas is ignited.

Steam may be supplied to the inlet 7 from any suitable source. Exhaust steam from the locomotive is preferably used. When the locomotive is at a terminal the steam may be taken primarily from the usual terminal steam line, and when the locomotive is idle the steam may be taken from the steam drum thereof. If high-pressure steam is used it is preferably reduced in pressure by passing it through a suitable pressure-reducing valve. As the steam flows through the tubes of the superheater it becomes highly superheated by the combustion of the gases in the fire box, but is maintained at a low pressure, due to the necessity of preventing a pressure or load in excess of the tensile strength of the nickel. The retort or re-action chamber is of comparatively large capacity so that the highly heated steam and fuel materials may be re-acted into gas without producing an undue internal pressure within it. The tensile strength of nickel is very low and the temperatures developed in this apparatus are very high, these temperatures being well above 1800° F. The inflowing saturated steam protects the lower header and the intake tubes of the superheater; and the flow of steam through the upper header, outlet tubes of the superheater, and through the outlet chamber of the lower header, is sufficiently rapid to protect the metal, under most operating conditions, from the extremely high heat of the fire box. Should the upper header of the superheater and the discharge tubes leading therefrom reach a temperature close to the degree of heat which would destroy the metal of the superheater, such a temperature would be sufficient to disassociate the elements of steam and free the hydrogen from the oxygen. The hydrogen will then be absorbed by the metal of the superheater and will protect the metal from the exterior heat of the fire box. At the lower temperatures the flow of steam will protect the metal of the superheater, and at the higher temperatures, the destructive temperatures, the hydrogen will serve as a protecting means.

The highly superheated steam flows at a low pressure into the lower end of the inlet pipe 27 of the retort and picks up the oil, or other hydrocarbon, and carries it upwardly within the pipe. The oil is discharged into the mass of upwardly flowing superheated steam and is carried up through the inlet pipe. Pure superheated steam passes into the pilot pipe 33 and is discharged through the nozzle 30 directly on the apex 22 at the top of the retort. This pilot jet of superheated steam spreads over the inner wall of the retort and is very highly heated. The wall of the retort is at a sufficiently high temperature to break down or disassociate the elements of the steam and separate the oxygen from the hydrogen, thereby providing substantially a blanket or film of hydrogen close to the wall of the retort. This blanket or film of oxygen and hydrogen remains substantially free from carbon oxides and other gases within the retort and a part of the hydrogen is absorbed by the nickel wall of the retort.

The oil or hydrocarbon and the superheated steam passing upwardly through the inlet pipe are also diverted by the apex 22 and the curved walls connected thereto, and are driven around within the retort. Gas re-action begins within the inlet pipe because of the highly superheated steam into which the oil is delivered. At the upper discharge end of the inlet pipe the gases and vapors contact with the highly superheated steam discharged through the nozzle. The mass of gas and vapors swirls around within the retort and the re-action is completed therein, due to the high temperature which surrounds the retort. The oxygen in the steam reacts with the carbon in the hydrocarbon thereby leaving the hydrogen of the steam nascent and a fixed gas is produced having an excess of hydrogen from a source independent of the hydrocarbon supply. From the interior of the retort the gas passes down through the tube 25 and out through the channels 24 and 35 and is then combusted as a pure gas, and the retort or re-action chamber is subject to a very high temperature running well above 2000° F. The gas in its downward passage through the outlet tube 25 maintains the pilot pipe 32 and the inlet pipe 27 at a very high temperature so that the discharge from the nozzle and the inlet pipe will be very highly heated. Air in sufficient quantities is supplied through the air openings 39.

If the temperature in the superheater is sufficiently high the steam will be disassociated and oxygen and hydrogen will flow to the inlet pipe 27. Oxygen and hydrogen will then also flow through the pilot pipe 32 and be discharged through the nozzle 30 directly on the apex 22 within the retort. The inflowing hydrogen and oxygen will take up

the oil and gas re-action will begin immediately within the pipe 27.

Heat taken up by the materials introduced into the retort is constantly replaced by heat transmitted from the fire box through the walls of the retort.

The upper end of the tube 25, which constitutes the outlet from the retort, is designed and located with the end in view of establishing within the retort commotion among and commingling of the materials delivered into the retort. The size of the retort is based upon the time element requirements of the re-actions.

In designing the apparatus so that it shall meet re-action time requirements, consideration must be given to temperatures, materials used and pressures established. The entrances into the retort, namely the pilot nozzle and the pipe 27, must be balanced in cross section with the exits from the retort. The volume contained within the retort must be equationed with the entrances and exits plus the speed of materials within the retort, to maintain a low pressure therein.

The steam and fuel are commingled, reacted, discharged in gaseous form, contacted with the required air quantities and then combusted within the fire box. The heat of the fire box imparts through the wall of the retort the required thermal values for sustaining the re-actions. The re-actions of the materials within the retort increase the heat therein, as is well known, so that the gas flows from the retort at a very high temperature. The size of the retort and its design create eddies and comminglings favorable to intimacies of contact between the materials introduced, and ensure the completeness of re-actions involved without undue pressure.

The oil ejector is so protected and maintained at a low degree of temperature by water cooling, or otherwise, that the cracking point of the oil is not reached; so that when the superheated steam, or the hydrogen and oxygen, flowing through the inlet pipe 27 comes into contact with the hydrocarbon, the oxygen and hydrogen immediately begin to re-act on the carbon and the whole volume of re-acting gas and vapor is sprayed over the apex 22 and continues around the retort. The oil is preferably heated before it is ejected into the inlet pipe 27, but the degree of heat is well below the cracking point of the oil.

Any suitable form of superheater that will withstand the high temperatures of the fire box may be employed, and said superheater may be arranged vertically or horizontally. If desired it may be formed of refractory material instead of metal.

The retort and the superheater may be formed of any metal having the same char-

acteristics, or substantially so, of nickel in the presence of hydrogen.

What I claim is:

1. A gas producing and burning apparatus comprising a combustion chamber, a steam superheater in said chamber, a retort or reaction chamber in the combustion chamber, a vertically arranged inlet pipe extending centrally up into said retort, means for conducting superheated steam from the superheater to the lower end of said inlet pipe, a vertically arranged nozzle centrally located in said inlet pipe near the upper end thereof, means for delivering superheated steam to said nozzle, means for delivering oil into the lower end of the inlet pipe, the retort being formed with a gas outlet at its lower end and surrounding the inlet pipe and the upper wall of the retort being formed on its interior with a centrally located downwardly extending apex, or inverted cone extending close to and directly over the upper discharge ends of the nozzle and the inlet pipe, a base supporting the retort, and gas channels connected at their inner ends to the discharge outlet from the retort, whereby gas generated within the retort will be discharged into the combustion chamber around the base of the retort.

2. A gas producing and burning apparatus comprising a combustion chamber, a steam superheater in said chamber, a retort or reaction chamber in the combustion chamber, a vertically arranged inlet pipe extending centrally up into said retort, means for conducting superheated steam from the superheater to the lower end of said inlet pipe, a vertically arranged nozzle centrally located in said inlet pipe near the upper end thereof, means for delivering superheated steam to said nozzle, means for delivering oil into the lower end of the inlet pipe, a discharge tube in the retort surrounding the inlet pipe and extending upwardly into the retort the lower end of said tube being open to form a gas outlet at the base of the retort and surrounding the inlet pipe, the upper wall of the retort being formed on its interior with a centrally located downwardly extending apex or inverted cone, extending close to and directly over the upper discharge ends of the nozzle and the inlet pipe, a base supporting the retort, and gas channels connected at their inner ends to the discharge outlet from the retort, whereby the gas generated within the retort will be discharged into the combustion chamber around the base of the retort.

3. A gas producing and burning apparatus comprising a combustion chamber, a retort or reaction chamber in the combustion chamber, a vertically arranged inlet pipe extending centrally up into said retort, means for conducting superheated steam to

the lower end of said inlet pipe, a vertically arranged nozzle centrally located in said inlet pipe near the upper end thereof, means for delivering superheated steam to said nozzle, means for delivering oil into the lower end of the inlet pipe, a discharge tube in the retort surrounding the inlet pipe and extending upwardly into the retort the lower end of said tube being open to form a gas outlet at the base of the retort and surrounding the inlet pipe, the upper wall of the retort being formed on its interior with a centrally located downwardly extending apex or inverted cone extending close to and directly over the upper discharge ends of the nozzle and the inlet pipe, a base supporting the retort, and gas channels connected at their inner ends to the discharge outlet from the retort, whereby the gas generated within the retort will be discharged into the combustion chamber around the base of the retort.

4. A gas producing and burning apparatus comprising a combustion chamber, a retort or reaction chamber in the combustion chamber, a vertically arranged inlet pipe extending centrally up into said retort, means for conducting steam to the lower end of said inlet pipe, a vertically arranged nozzle centrally located in said inlet pipe near the upper end thereof, means for delivering steam to said nozzle, means for delivering oil into the lower end of the inlet pipe, a discharge tube in the retort surrounding the inlet pipe and extending upwardly into the retort the lower end of said tube being open to form a gas outlet at the base of the retort and surrounding the inlet pipe, the upper wall of the retort being formed on its interior with a centrally located downwardly extending apex or inverted cone extending close to and directly over the upper discharge ends of the nozzle and the inlet pipe, a base supporting the retort, and gas channels connected at their inner ends to the discharge outlet from the retort, whereby the gas generated within the retort will be discharged into the combustion chamber around the base of the retort.

5. A gas producing and burning apparatus comprising a combustion chamber, a retort or reaction chamber in the combustion chamber, a vertically arranged inlet pipe extending centrally up into said retort, means for conducting steam to the lower end of said inlet pipe, a vertically arranged nozzle centrally located in said inlet pipe near the upper end thereof, means for delivering steam to said nozzle, means for delivering hydrocarbon into the lower end of the inlet pipe, the lower end of said retort being open to form a gas outlet at the base of the retort and surrounding the inlet pipe, the upper wall of the retort being formed on its interior with a centrally located

cated downwardly extending apex or inverted cone extending close to and directly over the upper discharge ends of the nozzle and the inlet pipe, and laterally extending gas channels connected at their inner ends to the discharge outlet from the retort, whereby the gas generated within the retort will be discharged into the combustion chamber around the base of the retort.

6. A gas producing and burning apparatus comprising a combustion chamber, a retort or reaction chamber in the combustion chamber, a vertically arranged inlet pipe extending centrally up into said retort, means for conducting steam to the lower end of said inlet pipe, a vertically arranged nozzle centrally located in said inlet pipe near the upper end thereof, means for delivering steam to said nozzle, means for delivering hydrocarbon into the lower end of the inlet pipe, the lower end of said retort being open to form a gas outlet at the base of the retort and surrounding the inlet pipe, the upper wall of the retort extending close to and directly over the upper discharge ends of the nozzle and the inlet pipe, and laterally extending gas channels connected at their inner ends to the discharge outlet from the retort, whereby the gas generated within the retort will be discharged into the combustion chamber around the base of the retort.

7. A gas producing and burning apparatus comprising a combustion chamber, a steam superheater in said chamber, a retort or reaction chamber in the combustion chamber, a vertically arranged inlet pipe extending centrally up into said retort, means for conducting superheated steam from the superheater to the lower end of said inlet pipe, a vertically arranged nozzle centrally located in said inlet pipe near the upper end thereof, means for delivering superheated steam to said nozzle, means for delivering oil into the lower end of the inlet pipe, a discharge tube in the retort surrounding the inlet pipe and extending upwardly into the retort the lower end of said tube being open to form a gas outlet at the base of the retort and surrounding the inlet pipe, the upper wall of the retort extending close to and directly over the upper discharge ends of the nozzle and the inlet pipe, a base supporting the retort, and gas channels connected at their inner ends to the discharge outlet from the retort, whereby the gas generated within the retort will be discharged into the combustion chamber around the base of the retort.

8. A gas producing and burning apparatus comprising a combustion chamber, a retort or reaction chamber in the combustion chamber, an inlet pipe extending into said retort, means for conducting steam to the inlet end of said inlet pipe, a nozzle centrally

located in said inlet pipe near the outlet end thereof, means for delivering steam to said nozzle, means for delivering hydrocarbon into the inlet end of the inlet pipe, the 5 said retort being formed with a gas outlet surrounding the inlet pipe, one wall of the retort being formed on its interior with an inwardly extending apex or cone extending close to and directly in line with the discharge 10 ends of the nozzle and the inlet pipe, and gas channels connected at their inner ends to the discharge outlet from the retort, whereby the gas generated within the retort will be discharged into the combustion chamber 15 around the retort.

9. A gas producing and burning apparatus comprising a combustion chamber, a retort or reaction chamber in the combustion chamber, an inlet pipe extending into 20 said retort, means for conducting steam to the inlet end of said inlet pipe, means for delivering hydrocarbon into the inlet end of the inlet pipe, the said retort being formed with a gas outlet surrounding the 25 inlet pipe, one wall of the retort being formed on its interior with an inwardly extending apex or cone extending close to and directly in line with the discharge end of the inlet pipe, means centrally located in 30 said inlet pipe near the outlet end thereof for delivering steam on said apex, and gas channels connected at their inner ends to the discharge outlet from the retort, whereby the gas generated within the retort will be 35 discharged into the combustion chamber around the retort.

10. A gas producing and burning apparatus comprising a combustion chamber, a retort or reaction chamber in the combustion 40 chamber, means for delivering mixed steam and fuel materials within the retort close to one wall thereof and means to deliver a jet of pure steam on the interior surface of one wall of the retort said jet of pure steam being arranged in the center of the volume of mixed steam and fuel materials and serving to spread a blanket or coating of pure steam over the interior surface of the retort.

11. A gas producing and burning apparatus comprising a combustion chamber, a retort or reaction chamber in the combustion chamber one wall of the retort being formed on its interior with an inwardly extending apex or cone, means for delivering 45 mixed steam and fuel materials within the retort directly and centrally on the said apex, and means to deliver a jet of pure steam directly and centrally on said apex said jet of pure steam being arranged in the center of the volume of mixed steam and fuel materials and serving to spread a blanket or coating of pure steam over and in direct contact with the interior surface of the retort.

12. A gas producing and burning appa-

ratus comprising a combustion chamber, a retort or reaction chamber in the combustion chamber the upper wall of the retort being formed on its interior with an inwardly and downwardly extending apex or cone, 70 means for delivering mixed steam and fuel materials within the retort directly and centrally on the said apex, and means to deliver a jet of pure steam directly and centrally on said apex said jet of pure steam being arranged in the center of the volume of mixed steam and fuel materials and serving to spread a blanket or coating of pure steam over and in direct contact with the interior surface of the retort.

13. A gas producing and burning apparatus comprising a combustion chamber, a retort or reaction chamber in the combustion chamber one wall of the retort being formed on its interior with an inwardly extending apex or cone, means for delivering mixed superheated steam and fuel materials within the retort directly and centrally on the said apex, and means to deliver a jet of pure superheated steam directly and centrally on 85 said apex said jet of pure superheated steam being arranged in the center of the volume of mixed superheated steam and fuel materials and serving to spread a blanket or coating of pure superheated steam over and in 90 direct contact with the interior surface of the retort.

14. A gas producing and burning apparatus comprising a combustion chamber, a retort or reaction chamber in the combustion chamber, a vertically arranged inlet pipe extending centrally up into said retort, a vertically arranged nozzle centrally located in said inlet pipe near the upper end thereof, the lower end of said retort being open to form a gas outlet at the base of the retort and surrounding the inlet pipe, the upper wall of the retort being formed on its interior with a centrally located downwardly extending apex or inverted cone extending close to and directly over the upper discharge ends of the nozzle and the inlet pipe, and laterally extending gas channels connected at their inner ends to the discharge outlet from the retort.

15. A gas producing and burning apparatus comprising a combustion chamber, a retort or reaction chamber in the combustion chamber, an inlet pipe extending into said retort, a nozzle centrally located in said inlet pipe near the outlet end thereof, the said retort being formed with a gas outlet surrounding the inlet pipe, one wall of the retort being formed on its interior with an inwardly extending apex or cone extending close to and directly over the discharge ends of the nozzle and the inlet pipe, and gas channels connected at their inner ends to the discharge outlet from the retort, whereby the gas generated within the retort will

be discharged into the combustion chamber around the retort.

16. A gas producing and burning apparatus comprising a combustion chamber, a 5 retort or reaction chamber in the combustion chamber, a vertically arranged inlet pipe extending centrally up into said retort, a vertically arranged nozzle centrally located in said inlet pipe near the upper end thereof, the lower end of said retort being open to form a gas outlet at the base of the retort and surrounding the inlet pipe, the upper wall of the retort extending close to and directly over the upper discharge ends of the nozzle and the inlet pipe; a base supporting the retort; and gas channels connected at their inner ends to the discharge outlet from the retort, whereby the gas generated within the retort will be discharged into the combustion chamber around the base of the retort. 10 15 20

17. A gas producing and burning apparatus comprising a combustion chamber; a steam superheater in said chamber; a retort or reaction chamber in the combustion chamber; a vertically arranged inlet pipe extending centrally up into said retort; means for connecting the superheater to the lower end of said inlet pipe; a vertically arranged nozzle centrally located in said inlet pipe near the upper end thereof; means for connecting the superheater to said nozzle; means for delivering fuel materials into the lower end of the inlet pipe; a discharge 25 30 35 40 45 50 tube in the retort surrounding the inlet pipe and extending upwardly into the retort, the lower end of said tube being open to form a gas outlet at the base of the retort and surrounding the inlet pipe, the upper wall of the retort being formed on its interior with a centrally located downwardly extending apex or inverted cone extending close to and directly over the upper discharge ends of the nozzle and the inlet pipe; a base supporting the retort; and gas channels connected at their inner ends to the discharge outlet from the retort, whereby the gas generated within the retort will be discharged into the combustion chamber around the base of the retort. 55 60 65 70 75

18. A gas producing and burning apparatus comprising a combustion chamber; a steam superheater in said chamber; a retort or reaction chamber in the combustion chamber; a vertically arranged inlet pipe extending centrally up into said retort; means for connecting the superheater to the lower end of said inlet pipe; a vertically arranged nozzle centrally located in said inlet pipe near the upper end thereof; means for connecting the superheater to said nozzle; means for delivering fuel material into the lower end of the inlet pipe; a discharge tube in the retort surrounding the inlet pipe and extending upwardly into the retort, the 60 65 70 75 80 85 90 95 100 105 110 115 120 125 130

lower end of said tube being open to form a gas outlet at the base of the retort and surrounding the inlet pipe, the upper wall of the retort extending close to and directly over the upper discharge ends of the nozzle and the inlet pipe; a base supporting the retort; and gas channels connected at their inner ends to the discharge outlet from the retort, whereby the gas generated within the retort will be discharged into the combustion chamber around the base of the retort. 75 80 85 90 95 100 105 110 115 120 125 130

19. A retort for a gas producing and burning apparatus, comprising a reaction chamber, a vertically arranged inlet pipe extending centrally up into said chamber, and a vertically arranged nozzle centrally located in said inlet pipe near the upper end thereof, the lower end of said retort being open to form a gas outlet at the base of the retort and surrounding the inlet pipe, the upper wall of the retort being formed on its interior with a centrally located downwardly extending apex or inverted cone extending close to and directly over the upper discharge ends of the nozzle and the inlet pipe. 80 85 90 95 100 105 110 115 120 125 130

20. A retort for a gas-producing and burning apparatus, comprising a reaction chamber; a vertically arranged inlet pipe extending centrally up into said chamber; a vertically arranged nozzle centrally located in said inlet pipe near the upper end thereof; and a discharge tube in the retort surrounding the inlet pipe and extending upwardly into the chamber, the lower end of said discharge tube being open to form a gas outlet at the base of the retort and surrounding the inlet pipe, the upper wall of the retort extending close to and directly over the upper discharge ends of the nozzle and the inlet pipe. 95 100 105 110 115 120 125 130

21. A retort for a gas-producing and burning apparatus comprising a reaction chamber, a vertically arranged inlet pipe extending centrally up into said chamber; a vertically arranged nozzle centrally located in said inlet pipe near the upper end thereof; and a discharge tube in the retort surrounding the inlet pipe and extending upwardly into the retort, the lower end of said discharge tube being open to form a gas outlet at the base of the retort and surrounding the inlet pipe, the upper wall of the retort being formed on its interior with a centrally located downwardly extending apex or inverted cone extending close to and directly over the upper discharge ends of the nozzle and the inlet pipe. 110 115 120 125 130

22. That improvement in the art of generating heat from petroleum in a combustion chamber with a nickel retort in said chamber and having an outlet into said chamber, consisting in commingling petroleum and superheated steam in the retort, heating said retort from the exterior to a 125 130

degree above the melting point of nickel and sufficient to cause the oxygen in the steam to react with the carbon in the hydrocarbon thereby leaving the hydrogen of the steam nascent, and igniting the gases outside the retort.

23. That improvement in the art of generating heat by combusting fuel in a combustion chamber with a nickel retort in said chamber and having an outlet into said chamber, consisting in maintaining a supply of fuel and superheated steam to said retort at low-pressure but of sufficient high temperature to cause the oxygen in the steam to react with the carbon in the hydrocarbon thereby leaving the hydrogen of the steam nascent, maintaining a supply of air to the fire-box, and burning the commingled air and reaction products in the fire-box.

24. That improvement in the art of generating heat from non-gaseous hydrocarbons in a combustion chamber with a retort therein having walls formed of hydrogen absorbing metal, which consists in passing non-gaseous hydrocarbon through the reaction chamber, maintaining a temperature in said chamber well above 1800 degrees F. to convert the hydrocarbon into gases while within the chamber, maintaining an excess of hydrogen in the chamber over that contained in the hydrocarbon supplied thereto to assist in the reaction of the hydrocarbon into gases and prevent destruction of the chamber walls, and burning the reaction products in the combustion chamber outside of the reaction chamber.

25. That improvement in the art of converting petroleum into fuel gases in a combustion chamber with a nickel retort in said chamber and having an outlet into said chamber, consisting in maintaining a low pressure supply of commingled petroleum and highly superheated steam products to the retort, maintaining a separate low pressure supply of highly superheated steam products to the retort, heating the retort to maintain therein a temperature above 1800 degrees F. to cause the oxygen in the steam to react with the carbon in the hydrocarbon thereby leaving the hydrogen of the steam nascent, and allowing the gaseous reaction products to pass freely from the retort.

26. The method of treating and combust-
ing non-gaseous carbonaceous fuel in a com-
bustion chamber with a nickel retort with-
in said chamber and having an outlet open
to said chamber, consisting in introducing
mixed steam and petroleum into the retort
at low pressure, supplying highly super-
heated steam products at low pressure sepa-
rately to said retort to produce a fixed gas
having an excess of hydrogen, burning the
reaction products issuing from said retort
in immediate proximity to the retort, and so
co-relating the supply of petroleum and
steam products with the retort capacity as
to generate and maintain a temperature in
the combustion zone around the retort above
the melting point of nickel.

In testimony whereof I hereunto affix my signature.

FRANCIS NESBITT POIGNAND.
